UNITED STATES PATENT OFFICE.

CONSTANTIN FRIEDRICH RÖBER, OF DRESDEN, GERMANY, ASSIGNOR TO "UNIVERSALLE" CIGARETTENMASCHINEN-FABRIK, J. C. MÜLLER & CO., OF DRESDEN, GERMANY.

MEANS FOR DRIVING THE SHAFTS OF CIGARETTE MACHINES.

Application filed July 18, 1924, Serial No. 726,888, and in Germany March 22, 1924.

This invention relates to means for intermittent driving of the shafts of cigarette machines and in particular the coiling mandrels of cigarette shell or case machines.

5 In intermittent rotation it is usual in the art to employ a rack adapted to be reciprocated suitably (for example by means of a crank and connecting rod mechanism) which meshes with a pinion mounted on the 10 shaft. If unidirectional rotation of the shaft is desired then during its return movement the rack is brought out of engagement with the pinion. The coiling mandrel of cigarette shell machines has already been 15 driven in this way.

Under the present invention a rack is used for driving the shaft of the coiling mandrel but in accordance with the present invention this rack is connected with a parallel crank 20 and connecting rod mechanism in such manner that the rack is moved in a plane which is normal to the plane of the pinion to be driven. Thus the line of the dead centres of the double crank and connecting rod mechanism lies in the plane of the pinion to be driven. As a result the rack in its movement into and out of engagement with the teeth of the pinion to be driven performs a 25 movement transverse to the plane of the pinion to be driven at the moment when the displacement of the rack in the direction of the plane of the pinion to be driven is equal to zero or approximately equal to zero. The parallel crank and connecting rod mechanism ensures a uniform movement of the 30 points of the rack which all perform the same circular movement. The rack does not require to be raised or lowered so that the controlling means which would otherwise be 35 necessary for the purpose is dispensed with.

The invention is illustrated in Fig. 1 in vertical transverse section and in Fig. 2 in horizontal section partly in plan.

As shown, the coiling mandrel 1 is driven 45 by the pinion gearing 2, 3 from the shaft 4 which carries the driving pinion 5 which rotates in a vertical plane. The rack 6 engages with this pinion at regular intervals in a manner to be described subsequently.

50 The ends of the rack are connected by the crank pins 7, 8 with two crank discs 9 and 10 rotating in a horizontal plane. The crank discs are mounted on the vertical spindles 11, 12, of which spindle 12 is driven by the

bevel gear 13, its rotary movement being 55 transmitted through the pinions 13^a, 14 and 15 on the spindle 11.

The line connecting the dead centres of the parallel crank and connecting rod mechanism is so disposed that it coincides with 60 the front face of the pinion 5 to be driven.

In Fig. 2 the direction of rotation of the crank discs is indicated by the arrows, and the rack 6 is shown in the position in which it has just moved out of engagement with the pinion 5. If now on further rotation of the crank discs the crank pins move into the other dead centre position the rack 6 passes directly in front of the pinion 5 to be driven. The rack thus has a movement 70 substantially at right angles to the plane of the pinion 5 so that the teeth of the rack engage in a smooth and frictionless manner with the teeth of the pinion 5. The same may be said of the disengaging movement 75 of the rack from the teeth of the pinion 5.

Having now particularly described and ascertained the nature of my said invention and in what manner the same is to be performed, I declare that what I claim is:— 80

1. In an intermittent motion mechanism, a pinion adapted to be rotated intermittently in one direction, a rack adapted to engage said pinion, means for imparting longitudinal movement to the rack, and causing a 85 sidewise movement to the rack in the same plane with the teeth of the pinion, whereby said rack will engage said pinion for driving it during the longitudinal movement thereof in one direction and will be moved into and out of engagement therewith by said sidewise movement.

2. In an intermittent motion mechanism, a pair of spaced crank disks, a connecting rod therebetween including a rack, means for rotating said disks so as to impart longitudinal and sidewise reciprocations to said connecting rod, a pinion adapted to be engaged to be rotated by said rack during its longitudinal movement in one direction and to be disengaged from the rack by the sidewise movement thereof in one direction and to be engaged again by the sidewise movement in the opposite direction following the return longitudinal reciprocating movement. 100

3. In an intermittent motion mechanism, a pinion adapted to be rotated intermittently in one direction, a rack adapted to engage 105

said pinion, means for imparting longitudinal reciprocation to said rack, and causing a sidewise reciprocation to said rack in a plane with the teeth of the pinion and to cause the rack to disengage the pinion.

4. In an intermittent motion mechanism, a pinion adapted to be rotated intermittently in one direction, a pair of spaced crank disks, a connecting rod including a rack, means for rotating said disks so as to impart longitudinal and sidewise reciprocation to said connecting rod, said sidewise reciprocation being in a plane with the teeth of the pinion, whereby the rack engages the pinion during its longitudinal movement in one direction and disengages from the pinion by the sidewise movement and to again engage the pinion by the sidewise movement in the opposite direction.
5. In an intermittent motion mechanism, including a pinion adapted to be rotated intermittently in one direction, a rack engaging said pinion, means for imparting longitudinal reciprocations to said rack and simultaneously causing the rack to move in a plane parallel with the teeth of the pinion, whereby the pinion is rotated by the rack during its entire longitudinal movement in one direction and to be engaged and disengaged therefrom by the sidewise movement at the beginning and ending of the longitudinal movement.

tudinal reciprocations to said rack and simultaneously causing the rack to move in a 25 plane parallel with the teeth of the pinion, whereby the pinion is rotated by the rack during its entire longitudinal movement in one direction and to be engaged and disengaged therefrom by the sidewise movement 30 at the beginning and ending of the longitudinal movement.

6. In an intermittent motion mechanism, an elongated pinion adapted to be rotated intermittently in one direction, a rack adapted 35 to engage said pinion, means for imparting a longitudinal reciprocation to said rack and simultaneously causing the rack to move sidewise in a plane with the teeth of the pinion and to cause the rack to disengage the 40 pinion when at a point of its movement in one direction and to engage the rack at the beginning of its movement in the same direction.

In testimony whereof I affix my signature.
CONSTANTIN FRIEDRICH RÖBER.
